UNITED STATES PATENT OFFICE.

STEPHEN H. FARNHAM, OF CHICAGO, ILLINOIS.

TYPE-WRITER.

No. 831,502.

Specification of Letters Patent.

Patented Sept. 18, 1906.

Original application filed May 17, 1902, Serial No. 107,732. Divided and this application filed January 23, 1905; Serial No. 242,356.

To all whom it may concern:

Be it known that I, STEPHEN H. FARNHAM, a citizen of the United States, residing at Chicago, in the county of Cook and State of Illinois, have invented a certain new and useful Improvement in Type-Writers, of which the following is a specification, the same being a division of my application, Serial No. 107,732, filed May 17, 1902.

This invention relates to a construction of type-writer more especially adapted and intended for the use of merchants and dealers generally in making a bill and charge record and an abstract of a skeleton ledger under various headings, but can be used for any class of type-writing work where various items make up a total and such total is to be carried to a classified list or abstract in condensed form under various headings, so that a total of the different headings may be produced consecutively with the bill, statement, report, or other record without the necessity of removing the blank for the abstract or the skeleton-ledger from the machine with the removal of a bill, statement, report, or other charge-record.

The objects of the invention are to construct a divided or sectional cylinder or roller platen one division or section of which is utilized for making thereon the bill, statement, report or other record and the other division or section of which is utilized for making the skeleton ledger and operating each division or section independently by means of actuating pawls or dogs and ratchet-wheels or disks, a ratchet-wheel or disk being used for each division or section of the cylinder or platen, to interlock the divisions or sections together and enable one pawl or dog and its ratchet-wheel or disk to advance both divisions or sections simultaneously, and to improve generally the construction and operation of the cylinder or platen and the actuating means connected therewith for enabling the work to be accomplished. The invention consists in the features of construction and combination of parts hereinafter described, and pointed out in the claims.

In the drawings, Figure 1 is a sectional plan view of the cylinder or platen and its actuating devices in one form of construction and arrangement; Fig. 2, an end elevation showing the dog or pawl and the stop for advancing the cylinder or platen in the construction and arrangement of Fig. 1; Fig. 3, a detail in sectional plan, showing a modified construction

and arrangement for mounting one division or section of the cylinder or platen on the other division or section; and Fig. 4, a detail in section of the abutting ends of the divisions or sections of the cylinder.

The cylinder or roller-platen can be of any diameter and length desired to suit the construction of type-writing machine and the work to be done. The cylinder or roller-platen as shown is constructed in two divisions or sections, one of which is of greater length than the other. The longer division or section A is made of an outer shell or covering *a*, of vulcanized rubber or other suitable material, and an inner tube or hollow center *a'*, made of wood or other suitable material. The division or section B of the cylinder or platen is made of an outer shell or covering *b*, of vulcanized rubber or other suitable material, and an inner tube or hollow center *b'*, of wood or other suitable material.

The diameter of the two divisions or sections of the cylinder is the same, so that when sections abut the diameter of the cylinder or platen as a whole will be uniform its entire length. The outer end of the division or section A has attached thereto a plate *A'* with a hub or bearing *A''*, and, as shown, the plate is secured in position by screws *a''*, entered into the wood portion or center of the cylinder division or section, and the hub or bearing is attached to the rod or shaft on which the cylinder or platen as a whole is mounted by a set-screw *a'''*, the end of which engages the shaft or rod. The inner or abutting end of the division or section A of the cylinder or platen has secured thereto a plate *C*, having a hub or enlarged center *c*, extending out from which and surrounding the shaft or rod on which the cylinder or platen is mounted is a sleeve *C'*, having adjacent to its outer end a hub or enlarged center *c'* in the construction shown in Fig. 1. The plate *C* is attached to the end of the division or section *A* of the cylinder or platen by screws *c''*, entered into the wood or hollow center of the division or section. The inner or abutting end of the division or section B of the cylinder or platen has secured thereto a plate *D*, having, as shown in Fig. 1, a central opening with a contact edge *d* to travel on the hub or enlarged center *c* of the plate *C* and furnish a support for the end of the division or section *B* and bring the periphery of the two divisions or sections in the same plane. The outer face of the plate *D* has a circumferential

- rim d' to contact the face of the plate C and reduce the friction between the two plates, the body of the plate D being cut away, so as to leave a space between the two plates.
- 5 The plate D is of a diameter to fit within the outer shell or covering of the division or section B, and the plate is attached in position by screws d^2 , entered into the wood or hollow center b' of the division or section.
- 10 A plate or disk E, having peripheral ratchet-teeth e , is attached to the hub or enlarged center e' of the sleeve C'. The plate or disk E has a rim or hollow hub e' , through which passes a locking-screw e^2 , the end of
- 15 which is entered into the hub or enlarged center of the sleeve, so that with the turning of the shaft or rod on which the sleeve is mounted the plate will be revolved or turned. A plate or disk F, having a series of peripheral
- 20 ratchet-teeth, is attached to the outer end of the division or section B of the cylinder or platen. This plate or disk F on its outer face has an annular rim or flange f' , through which passes a set-screw f^2 , by means of
- 25 which the plate or disk F and the division or section B of the cylinder or platen can be locked to the plate or disk E for the divisions or sections of the cylinder or platen to be simultaneously advanced, it being understood
- 30 that when the two plates or disks are not interlocked each division or section of the cylinder or platen can be advanced or turned independently. The plate or disk F is secured to the end of the division or section B of the
- 35 cylinder or platen by screws f^3 , entered into the wood or hollow center of the division or section, and the rim or flange f' on one side has an opening to permit access to the locking-screw e^2 for turning said screw. The
- 40 plate or disk E is locked to the sleeve C' of the plate C, which is secured to the end of the division or section A of the roller or platen, and the division or section A is locked to the rod or shaft on which the cylinder or platen as a
- 45 whole is mounted, so that with the turning of the shaft or rod the division or section A, the sleeve C', and the plate or disk E will be correspondingly turned; but such turning of the plate or disk E will not turn the plate or disk
- 50 F and the division or section B of the cylinder or platen unless the two plates or disks are interlocked.
- A stop G locks both of the plates or disks E and F against turning except as required
- 55 and also holds the cylinder or roller-platen in line position after each adjustment. This stop is fixedly attached at its outer end to the frame or carriage supporting the cylinder or roller-platen in the arrangement shown, and
- 60 the body of the stop is longitudinally slotted to have a side arm g and a side arm g' , both of which have an elasticity or yield. These arms are arranged for the arm g to be in line with the plate or disk E and the arm g' to be
- 65 in line with the plate or disk F, and each arm

at its forward or acting end has pivoted thereto a roller g^2 , which contacts and engages the teeth of the plate or disk, as shown in Fig. 3. The plate or disk E is given a line-by-line advance by a reciprocating dog or pawl H, the acting end h of which engages successively with the teeth e of the ratchet-plate or disk, and the plate or disk F is given a line-by-line advance by a dog or pawl I, the acting end i of which engages successively with the teeth f of the ratchet-plate or disk, each dog or pawl being actuated in any usual and well-known manner for operating the dog or pawl of a type-writer to advance the cylinder or roller-platen. The shaft or rod J, which carries the cylinder or roller-platen, in the arrangement shown in Fig. 1 passes through the sleeve C' and extends at each end beyond the end of the cylinder or platen as a whole and beyond the end of the carriage or frame carrying the cylinder or platen, and, as shown, each projecting end has fixed thereto a finger-knob J', by means of which the shaft or rod can be turned. The shaft is mounted in suitable bearings j on the ends of the carriage or frame and, as shown, is locked against endwise thrust or movement by collars j' and set-screws j^2 , interposed between the knobs and the ends of the carriage or frame. The carriage or frame K, which supports the cylinder or platen and its shaft or rod, in the form shown consists of a front bar k and end bars k' , the end bars having thereon the bearings j for the shaft or rod. Each end bar k' terminates in a cross head or piece k^2 , having ears k^3 , between which is a collar l on a pivoting-rod L, which allows the frame or carriage to be raised and lowered as usual.

The operation is as follows: The blank for the bill, statement, report, or charge-record is inserted in the machine on the division or section A of the cylinder or platen and the blank for the abstract, skeleton ledger, or other total memoranda or record wanted is inserted in the machine on the division or section B of the cylinder or platen. The bill, statement, report, or other record to be made is written on the blank therefor on the division or section A of the cylinder, which division or section is turned to be advanced line by line in the usual way of operating type-writers by the ratchet-plate or disk E and its actuating-pawl H, and during the advance of the division or section A with the ratchet-plates or disks E and F disconnected the division or section B of the cylinder or platen remains stationary or in a fixed position, being held in such position by the arm g' and its roller g^2 of the retainer or stop. After the entries have been made on the blank on the division or section A the total of such entries is to be transferred to the blank on the section or division B under the proper heading, which total is printed on the blank as usual in the use of type-writers. The com-

pleted bill, statement, report, or other record is removed from and a new blank for another record is inserted on the division or section A in the usual manner and the division or section A is turned and advanced in the usual way to make the entries on the blank, and during such advance the division or section B remains stationary or in a fixed position. After the second blank on the division or section A is completed the total thereof is transferred to the blank on the division or section B under the proper heading, the cylinder or platen being moved endwise in the usual way of moving a type-writer cylinder or platen. 15 A third, fourth, fifth, and any number of blanks for bills, statements, reports, or records are successively entered in the machine on the division or section A, and properly filled and the total of each transferred to 20 the blank on the division or section B after each filling of a blank on the division or section A, and when the entire number of bills, statements, reports, or other record have been printed on the division or section 25 A and the totals of the various records have been transferred to the blank on the division or section B that blank will be completed either in the form of an abstract or skeleton ledger or such other form of blank as may be 30 used. As for example: A merchant may desire to ascertain the total amount of groceries, fish, and meat sold daily, weekly, or monthly. If a monthly statement is wanted, added to from day to day, the operator will 35 after making the entry from the grocery sale- ticket, for instance, on the invoice and charge and putting the total of the groceries in the total-amount column carry the total to the blank of the abstract, statement, or skeleton 40 ledger to be kept and enter the same under the groceries-column of such abstract, statement, or skeleton ledger. The meats purchased are entered from the meat sale-ticket onto the invoice and charge entry and the total footed, and this total is carried to 45 the abstract, statement, or skeleton ledger and entered in the meat-column. The fish purchased are entered from the fish sale-ticket on the invoice and charge entry and the total footed and this total carried to the abstract, 50 statement, or skeleton ledger and placed in the fish-column, it being understood that the carriage is advanced or moved endwise in each case, as usual in operating a type- 55 writer, and that the division or section A is turned as usual for the line-spaces through the plate or disk E and its actuating dog or pawl, and that the division or section B is turned as usual for line-spacing by the disk 60 F and its actuating dog or pawl I in the construction and arrangement of Fig. 1. There may be three or four entries for groceries to make one total, two or three entries for meat to make the total, and two or three entries of 65 fish to make the total, each entry of the va-

rious purchases occupying separate line-spaces on the invoice and charge entry, and where these purchases have necessitated the advancement of the invoice or bill and charge blank or form in the regular way the division 70 or section A of the cylinder or platen will have been turned and advanced from eight to ten line-spaces, more or less, and the division or section B of the cylinder or platen carrying the abstract, statement, or skeleton ledger 75 will have remained stationary or in a fixed position during the entire operation and the three totals of groceries, fish, and meat purchased appear in the same line in their respective columns and will be advanced one 80 regular allotted line-space after the various purchases for each customer have been entered.

The bill and charge or monthly statement blank when completed can be removed from 85 the machine and another bill and charge or monthly statement entered into the machine on the division or section A of the cylinder or platen without disturbing the division or section B of the cylinder or platen occupied by 90 the itemized statement or skeleton ledger blank, it only being advanced one regular line-space after the entry has been made on each bill and charge or monthly statement blank. A complete skeleton ledger or itemized statement will thus be had at the end of 95 the day's work with an entry in at least one of the three columns on their regular desired space of the blank, which entries when computed will give the total amounts of groceries, meats, and fish sold for the day in the store or department, and these total amounts can be checked as a balance with the totals of the sales of the various salesmen in the 100 store or department to produce a safeguard 105 statement, so that the proprietor may know by comparing the total of the sales with the total of the skeleton ledger or monthly statement that every sale has been billed and recorded on the monthly statement and skeleton ledger. 110

The construction shown in Fig. 3 has the wood or hollow center portion a' extending the full length of the cylinder or platen, with the end A³ reduced in diameter to the length 115 of the division or section B. The outer covering b of the division or section B has an interior lining or backing b², with a turned rim or flange b³ at its end, into which is threaded the attaching-screw f² for the ratchet-plate 120 or disk F. The end of the wood or hollow center a' has entered thereinto a metal rim or band b⁴, and at the commencement of the reduced portion A³ of the cylinder or platen is a metal band b⁵, which bands b⁴ and b⁵ 125 form a bearing or track on which the division or section B of the cylinder or platen can turn, the bands b⁴ and b⁵ furnishing a protection for the wood or hollow center of the cylinder or platen. The other appliances 130

shown in connection with the construction of Fig. 1 can be used with the form of cylinder of Fig. 3.

The divided cylinder or platen, with the dogs and pawls and the ratchet-wheels or disks for advancing or turning each division or section thereof independently and for turning and advancing both divisions or sections simultaneously, enables a bill, statement, report, or other record to be made on one division or section and an abstract, monthly statement, skeleton ledger, or other memoranda to be made on the other division or section without changing the operating appliances and without removing the blank or form for the abstract, statement, skeleton ledger, or other memoranda from its division or section of the cylinder or platen until the record desired is completed, and the construction also allows the cylinder or platen to be used its full length, as in the ordinary use of a type-writer, by simply interlocking the divisions or sections so that both will be turned and advanced simultaneously.

What I claim as new, and desire to secure by Letters Patent, is—

1. In a type-writer, the combination of a divided cylinder or platen, ratchet-plates or disks one for each division or section of the cylinder or platen, and dogs or pawls one for each plate or disk for advancing the plate or disk, substantially as described.

2. In a type-writer, the combination of a divided cylinder or platen, a separable interlock between the divisions or sections of the cylinder or platen, ratchet-plates or disks one for each division or section of the cylinder or platen, and dogs or pawls one for each plate or disk for advancing the plate or disk, substantially as described.

3. In a type-writer, the combination of a divided cylinder or platen, a ratchet-plate or disk having a hub and attached to one division or section of the cylinder or platen, a ratchet-plate or disk having an annular rim and attached to the other division or section of the cylinder or platen, a screw for interlocking the hub and rim and connecting the two divisions or sections of the cylinder or platen as one, dogs or pawls one for each plate or disk for advancing the plate or disk, and stops or retainers one for each plate or disk for holding the divisions or sections of the cylinder or platen stationary or in a fixed position, substantially as described.

4. In a type-writer, a divided cylinder or platen consisting of a continuous center, a division or section fixed on the continuous center, and a division or section revolvably

mounted on the continuous center and means for giving each section an independent step-by-step advance, substantially as described.

5. In a type-writer, the combination of a divided cylinder or platen having a continuous center, a division or section fixed on the continuous center, and a division or section revolvably mounted on the continuous center, and means for intermittently advancing the continuous center and the division or section fixed thereon, and means for intermittently advancing the revolvably-mounted division or section, substantially as described.

6. In a type-writer, the combination of a divided cylinder or platen having a continuous center, a division or section fixed on the continuous center, and a division or section revolvably mounted on the continuous center, ratchet-plates or disks, one for the continuous center and one for the revolvably-mounted division or section, and means for actuating the ratchet-plates or disks, substantially as described.

7. In a type-writing machine, the combination of a platen-carrier; a platen-axle having bearings in said platen-carrier; a platen fixedly connected with said platen-axle; a second platen rotatably mounted on said platen-axle; line-spacing devices coöperating with the first-named platen; and separate line-spacing devices coöperating with the second-named platen.

8. In a type-writing machine, the combination of a platen-carrier; a platen-axle having bearings in said platen-carrier; a platen fixedly connected with said platen-axle; a second platen rotatably mounted on said platen-axle; line-spacing devices coöperating with the first-named platen; and separate line-spacing devices coöperating with the second-named platen and a platen-operating hand-wheel located outside the carrier.

9. In a type-writing machine, the combination of a platen-carrier; a platen-axle having bearings in said platen-carrier; a platen fixedly connected with said platen-axle; a second platen rotatably mounted on said platen-axle; line-spacing devices coöperating with the first-named platen; separate line-spacing devices coöperating with the second-named platen; and means for connecting the two platens so that both may be simultaneously actuated by either of said line-spacing devices.
